UNITED STATES PATENT OFFICE

152,233

DESIGN FOR A SHOWER SANDAL

Wallace D. Wilson, Long Beach, Calif.

Application March 22, 1948, Serial No. 145,269

Term of patent 14 years

(Cl. D7—7)

To all whom it may concern:

Be it known that I, Wallace D. Wilson, citizen of the United States of America, residing at Long Beach, California, county of Los Angeles, State of California, have invented a new, original, and ornamental Design for Shower Sandals, of which the following is a specification, reference being had to the accompanying drawing, forming a part thereof.

Fig. 1 is a perspective view of a shower sandal, showing my new design;

Fig. 2 is a plan view thereof; and

Fig. 3 is a bottom plan view of the same.

I claim:

The ornamental design for a shower sandal, substantially as shown.

WALLACE D. WILSON.
